UNITED STATES PATENT OFFICE.

WILLIAM BLACKWOOD, JR., OF DETROIT, MICHIGAN.

WASH-STAND.

SPECIFICATION forming part of Letters Patent No. 275,122, dated April 3, 1883.

Application filed November 15, 1882. (No model.)

To all whom it may concern:

Be it known that I, WILLIAM BLACKWOOD, Jr., a citizen of the United States of America, residing at Detroit, in the county of Wayne 5 and State of Michigan, have invented certain new and useful Improvements in Wash-Stands; and I do hereby declare the following to be a full, clear, and exact description of the invention, such as will enable others skilled in the 10 art to which it appertains to make and use the same.

This invention relates to certain improvements in stationary wash-stands used in buildings.

15 In the stationary wash-stands now in general use made of two essential parts—to wit, the bowl and marble slab—the flange of the bowl is made flat, and the marble slab, with a corresponding flat under surface, is bedded on 20 this flange of the bowl by means of plaster-of-paris to make a water-tight connection or joint. After a stationary wash-stand of this common structure has been in use for some time the splashing of water or leaky faucets 25 causes the plaster-of-paris to be worn away, so that the water on the slab running down to the edge of marble does not fall into the bowl, but follows the flat surface of bottom of slab backward until it reaches outside of bowl, and 30 then runs down on the floor, thus damaging the floor and ceiling under.

To obviate these serious difficulties is the object of my invention.

My invention therefore consists in a bowl 35 for a stationary wash-stand, formed with an upward-beveled flange to impede the flow of splash-water and return or conduct the same to the bowl.

My invention further consists in the combination of a marble slab for a stationary wash-stand, formed on its under side with a beveled recess, and a wash-bowl with a beveled flange 40 to fit into the beveled recess of the slab, whereby when splash-water strikes this connection or union of parts the water will return to the bowl, instead of working out between the joint.

The annexed drawing is a sectional view of portions of a wash-bowl and a marble slab, 45 showing my improvements applied.

In the annexed drawing, the letter A repre-

sents a bowl for a stationary wash-stand used in buildings. The upper edge of this bowl is made or formed with an upward-inclined flange, B, arranged to set in the recess of the 55 top slab, substantially as shown.

The letter C represents a marble or metallic slab, formed on its under surface around the bowl-opening, for receiving the flange of the bowl, with a depending angular or beveled recess, D, corresponding, or nearly so, with the upwardly-inclined beveled flange of the bowl, but made somewhat deeper and longer than the flange of the bowl, for the purpose hereinafter stated. This recess in the top slab extends from 60 the edge of the bowl-hole with an upward incline, a, and terminating with the vertical depending wall b, the incline being made longer than the width of the bowl-flange, the back wall of which sets against the vertical wall of the slab, 70 thus leaving the under surface of the incline in the slab projecting or depending over the edge of the basin. By this construction and connection it will be seen that liquids from the top of the slab will run down the inner face 75 of the slab and drop from the depending lip into the basin, instead of running back under the slab and in a short time loosening and removing the plaster-cement between the slab and the basin, and then finding its way to the 80 floor, causing dampness or doing actual damage to the floor and ceiling.

The ordinary bolts for supporting the wash-bowl to the slab are employed in connection with this improvement.

What I claim as my invention, and desire to secure by Letters Patent, is—

1. A wash-stand bowl formed with an upward beveled or inclined flange, substantially as described.

2. The combination of a wash-bowl formed with an upward-beveled flange, and a top slab formed with an upward-beveled recess to receive the beveled or inclined flange of the wash-bowl, substantially as described.

In testimony whereof I affix my signature in presence of two witnesses.

WILLIAM BLACKWOOD, JR.
